R. N. MAXWELL

GAME

Filed June 28, 1922

Inventor
Rudolph N. Maxwell

By *Walter J. Murray*
Attorney

UNITED STATES PATENT OFFICE.

RUDOLPH N. MAXWELL, OF CINCINNATI, OHIO.

GAME.

Application filed June 28, 1922. Serial No. 571,365.

To all whom it may concern:

Be it known that I, RUDOLPH N. MAXWELL, a citizen of the United States of America, and a resident of Cincinnati, in the county 5 of Hamilton and State of Ohio, have invented a new and useful Improvement in a Game, of which the following is a specification.

My invention relates to games of the type 10 wherein movable bodies such as balls, must be lodged in individual pockets in order to end the game.

An object of my invention is to provide a simple and attractive device of this kind.

Another object of my invention is to provide a device which is simple in construction 15 and may be readily assembled.

These and other objects are attained by means described herein and disclosed in the 20 accompanying drawing, in which:

Fig. 1 is a perspective view of a device embodying my invention.

Fig. 2 is a sectional view on line 2—2 of 25 Fig. 1.

The base 3 carries sides 4 and 5, and ends 6 and 7, the sides and ends supporting a transparent cover, such as a plate of glass 8, and whereby a chamber 9 is formed within the device. The sides and ends may be 30 integral with the base, and be bent thereupon as shown in Fig. 2 and a suitable retaining band 10 may be mounted about the sides and ends and have flanges 11 and 12 formed on it, which flanges over-lap the base and plate, thereby retaining the parts 35 in their proper relation. The ends of the band may be secured upon one another in any suitable manner, such as by slotting one end of the band, as shown at 13, and forming 40 a tongue 14 on the other end of the band, which tongue may be inserted thru the slot, and be turned or bent as shown in Fig. 1. The slotted end of the band is also turned upon itself as shown in Fig. 1.

45 Mounted upon the base, and contained within the chamber 9 are a series of strips 15, 16 and 17 all of substantially the same shape. Each strip comprises a substantially U shaped body 18, the free ends 19 and 20 formed on the arms 21 and 22, being turned upon the arms and extending in substantial parallelism with the arms, whereby there are formed auxiliary pockets 22 adjacent the mouth 23 of the U shaped structure, and a seat or main pocket 24 at the base of the U shaped structure. At the mouth 23 of the channels 25 formed between the arms

21 and 22 is formed a depression 26, in which the movable elements such as balls 27, may lodge. Spots 28 are disposed within the 60 channels 25 at the seats 24, and designate the positions assumed by the balls 27 when the game is finished. Adjacent strips 18 have their mouths 23 disposed so as to open at opposite ends of the device. The turned 65 over end of one of the arms is disposed in substantial alignment with the turned over end of one of the arms of the next adjacent strip, the ends being spaced as shown at 29, thereby providing a passage between adjacent strips thru which the balls 27 may pass. The object of the game is to lodge 70 one each of the balls 27 in one each of the pockets 24. The depressions 26 serve to check the entry of the balls into the channels 25. The auxiliary pockets 22 serve to catch the balls 27 and hinder the free movement of the balls end-wise of the 75 device.

What I claim is:

1. In a game of the class described the combination of a series of substantially U shaped strips having a main pocket formed at their base, the arms of the strips being turned upon themselves at their free ends, 80 whereby to form auxiliary pockets adjacent the ends of the arms, the strips being disposed with their arms in substantial parallelism one with the other, adjacent strips having their main pockets disposed at opposite ends of the device, and movable bodies adapted to be lodged in the pockets. 85

2. In a game of the class described the combination of a series of U shaped strips having their arms extending in parallelism 90 and mounted adjacently one to the other, the strips being so formed as to provide pockets at the bases of the strips, and a pair of auxiliary pockets at the heads of each of the strips, the pockets being formed by 95 portions of the strips extending in substantial parallelism with one another, adjacent strips having their auxiliary pockets disposed at opposite ends of the device, the ends of the strips being spaced from the 100 ends of the next adjacent strips, and balls adapted to lodge in the pockets and pass between the ends of adjacent strips. 105

3. In a device of the class described the combination of a base, a series of U shaped strips mounted on the base having the free 110 ends of the arms turned outwardly and downwardly upon themselves whereby to extend in substantial parallelism with the un-

turned portion of the arms and to form auxiliary seats at the upper ends of the arms, and a main pocket at the base of the arms, the strips being mounted adjacent one another and having their arms disposed in substantial parallelism one with the other, whereby adjacent strips have their mouths opening to opposite ends of the base, the turned upper arm of one strip being aligned with and spaced from a turned upper arm

of the next adjacent strip, the base having depressions formed in it adjacent the mouths of the strips, and a ball for each of the strips adapted to be moved over the base and to be lodged in the pockets. ¹⁵

In testimony whereof I have hereunto subscribed my name this 23rd day of June, 1922.

RUDOLPH N. MAXWELL.
